UNITED STATES PATENT OFFICE.

WILLIAM W. TALBERT, OF CHICAGO, ILLINOIS, ASSIGNOR TO THE UNION SWITCH & SIGNAL COMPANY, OF SWISSVALE, PENNSYLVANIA, A CORPORATION OF PENNSYLVANIA.

RAILWAY SIGNALING.

1,263,624.

Specification of Letters Patent. Patented Apr. 23, 1918.

Application filed June 2, 1913. Serial No. 771,149.

To all whom it may concern:

Be it known that I, WILLIAM W. TALBERT, a citizen of the United States, residing at Chicago, in the county of Cook and State of Illinois, have invented certain new and useful Improvements in Railway Signaling, of which the following is a specification.

My invention relates to railway signaling and particularly to signaling for stretches 10 of single track over which traffic moves in both directions.

I will describe one form of railway signaling embodying my invention and will then point out the novel features thereof 15 in claims.

The accompanying drawing is a diagrammatic view showing one form of railway signaling embodying my invention.

Referring to the drawing, 1 and 2 designate the track rails of a railway track, which track is divided into successive sections of which three sections A, B and C are shown. As here shown, the limits of these sections are determined by insulated joints 21 in 25 both of the lines of track rails, but it is understood that the limits of the sections may be defined in other ways. Each of these track sections is provided with a track circuit comprising, as usual, a battery 3, the track rails of the section, and a track relay 4; although I have herein shown only one track circuit for each section A, B, and C, it is understood that any or all of these sections may, if desired, be provided with two 35 or more track circuits.

Traffic through the stretch in the direction indicated by the arrow is governed by signals S, S' and S², located respectively at the entrance ends of sections A, B and C; traffic in the opposite direction through sections B and A is governed by a signal S³. As here shown, signals S² and S³ are each adapted to assume two positions, horizontal and vertical, indicating respectively "stop" and "proceed"; and signals S and S' are each adapted to assume three positions, horizontal, inclined, and vertical, indicating respectively "stop," "proceed with caution," and "proceed." It is understood that these 50 two latter indications are both "proceed" indications, the former of the two meaning that the next signal or some other signal in advance indicates "stop."

Signal S' operates two circuit controllers 55 9 and 10 which are reversed while the signal

is moving between the horizontal and inclined positions and vice versa, and a third circuit controller 11 which is closed only when the signal is in the "stop" position. Signal S² operates a pole-changer 13. 60

Signal S is controlled by a polarized line relay 5, and signal S' is controlled by a polarized line relay 6. Signals S² and S³ are controlled respectively by line relays 7 and 8 which, however, as here shown are 65 not polarized.

The circuit for the inclined or "proceed with caution" position of signal S is from battery 22 through wire 23, contact 24, wire 25, signal S, wire 27 to battery 22; the circuit for the vertical or "proceed" position of this signal is from battery 22 through wire 23, contact 24, contact 52, wire 26, signal S, wire 27 to battery 22. The circuits for the control of signal S' are similar to those just 70 traced for signal S. The circuit for the control of signal S² is from battery 68 through wire 69, contact 70, wire 71, signal S², wire 72 to battery 68. The circuit for the control of signal S³ is similar to that just traced for 80 signal S².

The circuit for line relay 5 of signal S is from battery 12 through pole-changer 13, wire 14, contact 15, wire 16, circuit controller 9, wire 17, contact 18, wire 19, relay 85 5, wire 20, common wire 0, wire 51, pole-changer 13 to battery 12. When pole-changer 13 is in the position in which it is shown in the drawing, the positive side of battery 12 is connected with wires 14 and 17, 90 and the polarity of the current through relay 5 is then such that the polarized armature 52 of this relay is closed so that signal S is in the vertical position indicating "proceed." 95

The circuit for line relay 6 of signal S' is from battery 12 through pole-changer 13, wire 14, contact 15, wires 16 and 49, relay 6, wire 50, common wire 0, wire 51, pole-changer 13 to battery 12. With the pole-changer 13 in the position shown in the drawing, the polarity of the current through relay 6 is such that its polarized armature contact is closed so that signal S' is in the vertical position indicating "proceed." 100

The circuit for line relay 8 of signal S³ is from battery 29, through wire 30, contact 31, wire 32, back contact point 33 of relay X, wire 34, contact 35, wire 36, relay 8, wire 37, common wire 0 to battery 29. 105

X is an auxiliary relay for the control of signal S in a manner hereinafter explained. This relay X is provided with a "pick-up" circuit and a "holding" circuit. The pick-up circuit is from battery 28, through wires 38 and 39, back contact point 40 of track relay 4 for section A, wire 41, contact 42 of relay 6, wire 43, relay X, wires 44 and 45 to battery 28. It will be seen that this pick-up circuit is closed only when relay 6 is energized and track relay 4 of section A is deenergized. The holding circuit for relay X is from battery 28, through wires 38 and 46, contact 47 of relay X, wire 48, back point 15 of contact 42 of relay 6, wire 43, relay X, wires 44 and 45 to battery 28. It will be seen that this holding circuit is closed only after relay X has been picked up and only while relay 6 is deenergized.

20 The operation of the system is as follows: Assuming first that a car or train passes along the track in the direction indicated by the arrow; as such car or train enters track section A it opens track relay 4 for this section, thereby opening the circuit of line relay 8 so that signal S³ changes to "stop" indication and also opening the circuit of line relay 5 so that signal S changes to "stop" indication. The opening of track relay 4 also closes the pick-up circuit of auxiliary relay X so that this relay then becomes energized. As such car or train enters track section B, it opens track relay 4 of this section, thereby opening at this point the circuit of line relay 8 so that signal S³ continues to indicate "stop" as long as the car or train occupies track section B. The opening of track relay 4 of section B also opens the circuit of line relay 6 so that signal S' then changes to "stop" indication. This change of signal S' changes circuit controllers 9 and 10 to the position indicated in dash lines and closes circuit controller 11. The opening of line relay 6 closes the holding circuit for auxiliary relay X so that even after the entire car or train has passed out of the track section A this auxiliary relay X remains energized. The closing of circuit controller 11 and the reversal of circuit controller 10 closes the following circuit for line relay 5: from negative side of battery 28, through wire 45, circuit controller 11, wire 53, contact 54 of relay X, wires 55 and 17, contact 18, wire 19, relay 5, wire 20, common wire 0, wires 50 and 56, circuit controller 10, wire 57, to positive side of battery 28. The negative side of battery 28 is now connected with wire 17 so that the polarity of the current in relay 5 is such that 50 the polarized contact 52 of this relay is open. The neutral contact 24 of this relay is, however, closed, so that signal S then moves to the inclined position indicating "proceed with caution."

55 As the car or train enters track section C,

it opens track relay 4 for that section, thereby deenergizing line relay 7 so that signal S² moves to "stop" position.

When the entire car or train leaves section B, the closing of track relay 4 of that section closes the circuit of line relay 6; since however signal S² is then in the "stop" position, pole-changer 13 has been reversed so that the negative side of battery is then connected with wire 16, and the polarity of the current in relay 6 is then such that the polarized armature of this relay is open; the neutral armature of this relay closes, however, so signal S' changes to inclined position, thereby reversing circuit controllers 9 and 10. When relay 6 closes, as just described, the opening of the back point of contact 42 of this relay opens the holding circuit of auxiliary relay X so that the latter relay opens, and thereby opens at contact 54 the circuit last traced for line relay 5. As soon, however, as relay 6 has closed, and before circuit controller 9 has been reversed, a temporary shunt is closed for the circuit of relay 5 as follows: From negative side of battery 28 through wire 45, contact 58 of relay 6, wire 59, circuit controller 9 to wire 17; this shunt keeps relay 5 energized between the time that relay X opens and the time that circuit controller 9 is reversed. As soon as circuit controller 9 reverses, line relay 5 is disconnected from battery 28 and is connected with battery 12, the circuit for this relay being then the same as first traced hereinbefore, except that pole-changer 13 is reversed so that the polarity of the current in relay 5 is still such that polarized contact 52 is open, hence signal S continues to indicate "proceed with caution."

The closing of track relay 4 of section B and the consequent opening of auxiliary relay X closes the circuit of line relay 8 so that signal S³ then moves to "proceed" position. Since the circuit of line relay 8 for signal S³ is controlled by a back contact point of relay X, it will be seen that if this relay X is at any time energized by accident, signal S³ will be caused to indicate "stop."

After the entire car or train has passed out of section C, track relay 4 of this section closes, thereby causing line relay 7 to close, which in turn causes signal S² to change to "proceed" position. This movement of signal S² reverses pole-changer 13 to the position in which it is shown in the drawing so that line relays 6 and 5 are then energized by current of such polarities that their polarized contacts are closed so that signals S and S' then change to the vertical position indicating "proceed."

Assuming now that a car or train passes along the track in the direction opposite to that indicated by the arrow. When such car or train enters track section C, it opens track relay 4, thereby causing signal S² to

change to "stop" indication. This movement of signal S^2 reverses pole-changer 13, thereby causing signals S and S' to change to the inclined position for reasons hereinbefore explained. As the car or train enters track section B, it opens track relay 4 of this section, thereby opening the circuit for line relay 8 so that signal S^2 then changes to "stop" indication. The opening of this track relay also opens the circuit of line relay 6, causing signal S' to change to "stop" indication. The opening of this track relay also opens the circuit of line relay 5, and since auxiliary relay X and line relay 6 are open, neither the auxiliary nor the temporary circuit for line relay 5 is closed, hence signal S changes to "stop" indication. When the entire car or train leaves section C, track relay 4 of that section closes so that signal S^2 changes to "proceed" indication, thereby again reversing pole-changer 13.

As the car or train enters section A, the opening of track relay 4 of this section holds open at this point the circuits for line relays 5 and 8 so that signals S and S^2 continue to indicate "stop".

When the entire car or train has passed out of section B, the closing of track relay 4 of that section closes the circuit of line relay 6 the polarity of the current in which is then such that signal S' changes to "proceed" indication. Line relay 6 now being closed, and track relay 4 of section A being open, the pick-up circuit for auxiliary relay X is closed, but the closing of this relay obviously has no effect on signal S because the circuit for line relay 5 is held open at track relay 4.

After the entire car or train has left track section A, the closing of track relay 4 for this section closes the circuits for line relays 5 and 8 so that signals S and S^2 then change to "proceed" indication and the parts of the apparatus again assume the positions in which they are shown in the drawing.

It will be seen from the foregoing that as a car or train proceeds along the track in the direction indicated by the arrow, auxiliary relay X is closed while such car or train occupies track section A and remains closed as long as the car or train occupies track section B; but while a car or train proceeds along the track in the opposite direction, the auxiliary relay X is not closed while such car or train occupies track section B; hence, it will be seen that during the movement in the direction indicated by the arrow signal S indicates "stop" only while the car or train occupies track section A, but that during movement in the opposite direction signal S indicates stop while the car or train occupies either track sections B or A.

Although I have herein shown and described only one form of railway signaling embodying my invention, it is understood that various changes and modifications may

be made therein within the scope of the appended claims without departing from the spirit and scope of my invention.

Having thus described my invention, what I claim is:

1. In combination, a stretch of railway track, two track sections, track relays and sources of current connected with the rails of the track sections, a signal for governing traffic in one direction through said sections and adapted to indicate stop and proceed, a circuit for said signal which circuit is controlled by the track relays for both sections, a branch for said circuit for removing the control of said signal circuit from the track relay of the second section in advance of the signal, means comprising an auxiliary relay for closing said branch, means controlled by the track relays when operated in one sequence by the passage of a car or train through the stretch in the direction in which said signal governs traffic for energizing said auxiliary relay and rendering the remainder of the last mentioned means operative whereby said signal changes to proceed when such car or train leaves the first section in advance of the signal, said means being inoperative to energize the auxiliary relay when the track relays are operated in another sequence by the passage of a car or train through the stretch in the other direction whereby said signal is caused to indicate stop while such last-mentioned car or train occupies either section, a second signal for governing traffic in the opposite direction through the second section in advance of the first signal, and a controlling circuit for said second signal which circuit is controlled by a back contact of said auxiliary relay and by a track relay for said second section in advance of said first signal.

2. In combination, a stretch of railway track, two track sections, track relays and sources of current connected with the rails of the sections, an auxiliary relay, means controlled by said track relays when operated in one sequence by the passage of a car or train through the stretch in one direction for energizing said auxiliary relay while the car or train occupies the first of said sections and for holding it energized while the car or train occupies the second section, said means being ineffective to energize the auxiliary relay when the track relays are operated in another sequence by the passage of a car or train in the other direction until the car or train has passed out of the said second section and into the said first section, a signal governing traffic through the said second section in the said second-mentioned direction, and a circuit for controlling said signal which circuit is controlled by a back contact of said auxiliary relay.

3. In combination, a stretch of railway track, two signals located at different points

for governing traffic in the same direction through said stretch, a signal relay for each signal, a signal relay circuit extending through the stretch and including said relays in multiple, said circuit also including a main source of current adjacent the end at which traffic in the said direction leaves the stretch, track circuits for the stretch including track relays for controlling said signal relay circuit, an auxiliary source of current located adjacent the forward signal, and

means for opening the signal relay circuit adjacent the forward signal and connecting the said auxiliary source of current with the portion of the circuit extending to the 15 rear from said point.

In testimony whereof I affix my signature in presence of two witnesses.

WILLIAM W. TALBERT.
